Des. 241,816
Patented Oct. 12, 1976

241,816

DISPENSING CONTAINER FOR A SHAVING COMPOSITION OR THE LIKE

Yoshinari Kusakawa, 1-34-23 Kamiikedai,
Otaku, Tokyo, Japan

Filed Mar. 18, 1975, Ser. No. 559,622

Term of patent 14 years

Int. Cl. D9—01

U.S. Cl. D9—9

FIG. 1

FIG. 2

FIG. 3

FIG. 4

FIG. 1 is a perspective view of a dispensing container for a shaving composition or the like showing my new design;

FIG. 2 is a top plan view;

FIG. 3 is a rear elevational view; and

FIG. 4 is a side elevational view thereof.

I claim:

The ornamental design for a dispensing container for a shaving composition or the like, as shown.
